METHOD AND APPARATUS FOR GRINDING LENSES

Benjamin Liebowitz, Lewisboro, N. Y.

Application September 18, 1942, Serial No. 458,843

13 Claims. (Cl. 51—111)

This invention relates to methods and apparatus for the grinding and polishing of lenses.

In current practice, after the lens blanks have been rough ground and smooth ground by hand operations, it is customary to mount the partly finished lens on a "block" by means of pitch. The block is then placed on a rotating spindle and the exposed surface is "fine ground" by means of an oscillating lap, after which it is carefully cleaned to remove all abrasive particles and transferred to a "polishing" spindle. After the polishing of this exposed surface has been completed, the lens is removed from the block, soaked in alcohol to remove the pitch, varnished or shellacked on the finished surface, re-mounted on a block with the varnished surface against the pitch, and the above mentioned operations of fine grinding and polishing are repeated. After the second surface has been polished, the lens must again be removed from the block, soaked in alcohol to remove the pitch and the varnish, and is then ready for the edging operation.

In my improved method and with my improved apparatus, both surfaces of the lens are operated on simultaneously and the mounting of the lens on a block is eliminated; in fact, all use of pitch is eliminated except in so far as "pitch laps" may be used for the polishing operation.

The production advantage of my method is obvious where the lenses are such that they are ordinarily fine-ground and polished singly. In the case of small lenses such that the solid angle subtended by the lens surface is small, it is customary in ordinary methods to mount a plurality of like lenses on one block simultaneously, so that a material advantage is gained in the current method by fine grinding and polishing a group of lenses at a time, where that is feasible. However, the time required to "polish out" a group of lenses of this sort is generally much longer than the time required to polish out the lenses individually, so that, although there is a substantial gain in group fineing and polishing, nevertheless the gain is not by any means proportional to the number of lenses in the group. On this account, in many cases even as to such small lenses, my method and machine offer a production advantage over conventional group processing because of the gain in time and space resulting from the elimination of necessity of the mounting of the lenses on heads, as well as from the fact that both surfaces of the lens are worked simultaneously. My method and apparatus offer certain other advantages which result in improved

quality; that is to say, by my method and apparatus it is less difficult to obtain precision surfaces than by conventional methods, for reasons which will hereinafter be set forth.

5 The objects of my invention are to gain the advantages set forth and to achieve other ends as will hereinafter be explained.

In the accompanying drawings which form part of this specification,

10 Figure 1 is a diagrammatic view through a conventional lap operating on one surface of a lens conventionally mounted on a block;

Fig. 2a is a diagrammatic view showing two laps in accordance with my invention working simultaneously on the surfaces of a bi-convex lens of unequal surface radii;

Fig. 2b shows the same system as Fig. 2a after it has undergone an appropriate displacement;

15 Figs. 3a and 3b are corresponding diagrammatic views of the application of my invention to a bi-convex lens with equal surface radii;

Figs. 4a and 4b are corresponding diagrammatic views of the application of my invention to a plano-convex lens;

20 Figs. 5a and 5b are corresponding diagrammatic views of the application of my invention to a concavo-convex lens. (These diagrammatic views of Figs. 2a-5b inclusive cover a sufficiently large number of different type lens surface combinations to illustrate how the method and principles of the invention can be applied in all cases.)

25 Fig. 6 is a cross-section through a machine which is adapted to carry out the operations indicated in diagrams of Figs. 2a and 2b, and 4a-5b inclusive;

Fig. 7 is a cross-section taken on the line 7—7 of Fig. 6 and viewed in the direction of the arrows;

30 Fig. 8 is a cross-section through the "gear box," taken at right angles to the cross-section shown in Fig. 6, and Fig. 9 to a top plan view of the gear box;

Fig. 9a is a bottom plan view of the "gear box" and associated parts;

35 Fig. 9b illustrates diagrammatically the motion imparted by the "gear box" to the driving member for one of the laps used in machines embodying my invention; and

40 Fig. 10 shows an elevation partly in section, and Fig. 11 a plan along line 11—11 of Fig. 10 of a modified mechanism adapted to the "parallel" case of Figs. 3a, 3b.

45 The conventional system as shown diagrammatically in Fig. 1 will be briefly described in

order to bring out certain force relationships. The lens 1 is mounted by means of the pitch layer 2 on the head 3. Pressed against the lens by means of the ball pin 5 is the lap 4. The ballpin 5 is carried in the boss 6 of an arm (not shown) which is oscillated back and forth roughly parallel to the plane of the drawing. The center of the lap surface and of the lens surface being ground or polished is at C_1 . The ball 5a of the ballpin has its center at C_2 . In addition to the weights of the boss 6 and its arm, pin 5 and lap 4, other weights or springs (not shown) are frequently employed to increase the pressure between the lap and the lens.

In order to study the forces involved in this conventional system, let us first assume that the contact area between lens 1 and lap 4 is frictionless and likewise the contact area between the ball 5a and its socket in the lap 4. Under these circumstances, the pressure at the spherical surfaces is normal to those surfaces and the resultant force between the lens 1 and lap 4 is directed along the line C_1C_2 ; likewise the resultant force between the ball 5a and its socket is directed along the same line. This force has a lateral component which is imposed on the ballpin and which is taken up by the arm carrying the boss 6; in order to avoid confusion, this component is not indicated in Fig. 1. Now imagine that the oscillating arm is traveling leftward, as shown by the arrow A-1, and consider the effect of the frictional forces at the spherical surface of the lap 4. Since the lap is moving leftward, the frictional forces tend to push the lens leftward, and the corresponding reaction on the lap is to the right, as shown by the small arrows A-2. These frictional forces will have a resultant force which is roughly indicated by the dotted arrow A-3 (plus a small couple which is generally negligible). In order to overcome this frictional force, there must be applied at the ballpin center C_2 an equal and opposite force indicated by the arrow A-4. The forces A-3 and A-4 constitute a couple which tends to rock the lap 4; that is, it tends to lift the trailing end of the lap and to cause the leading edge of the lap to press harder on the lens 1. This causes an unequal distribution of pressure over the area of contact between lens and lap 4, and, if the coefficient of friction becomes sufficiently high, it will prevent the operation of the machine by actually rocking the lap 4 against the vertical forces imposed by the ballpin 5, since the arm 6 which carries the ballpin 5 is free to move vertically. That is to say, frictional forces between the lens 1 and lap 4 give rise to a force couple whose magnitude is equal to the product of the resultant frictional force times the approximate distance from the lens surface engaging lap 4 to the center C_2 of the ballpin; this force couple gives rise to a non-uniform distribution of pressure between said lens surface and said lap; and it may under extreme conditions of friction prevent operation of the machine entirely by actually rocking the lap 4 away from contact with the said lens surface except at one edge or the other where it would tend to "dig in." Corresponding analysis of the forces will be made hereinafter for a system operating under my improved method.

The frictional forces are not the only source of non-uniform pressure distribution between the lap 4 and the lens 1. Due to the fact that the line of action of the impressed force is always directed along the line C_1C_2 (disregarding fric-

tion), and due to the fact that generally the line C_1C_2 does not pass through the center of the area of contact between the lens and the lap, the resulting pressure distribution can not be uniform. 5 This second source of non-uniform pressure distribution is substantially unchanged in my improved method, but, under suitable operating conditions, it is not harmful.

Referring now to Fig. 2a, which is illustrative 10 of principles embodying my invention, 11 is a lens whose lower surface has the radius r_1 centered at C_1 , and whose upper surface has the radius r_2 centered at C_2 . 12 is a lower lap having a spherical surface which is complementary to the lower surface of the lens, and 13 is an upper lap whose surface is complementary to the upper surface of said lens. I have chosen r_2 greater than r_1 . Now, let us suppose that the upper lap is given an angular displacement about 15 an axis passing through the center C_1 and perpendicular to the plane of the sheet of drawing. This displacement will carry the lens 11 to the position shown in Fig. 2b and the upper lap into the position shown by the dotted lines in said 20 figure. The center of curvature C_2 of the upper lap has then moved to the position C_2' so that the axis of the upper lap now has the position C_1C_2' . In this movement, the upper lap has not moved with respect to the lens. I will represent this 25 angular displacement by a_1 . Now let the upper lap 13 be given an angular displacement about its new center C_2' to the full line position of Fig. 2b carrying its axis from the position $C_2'C_1$ to the position $C_2'P$. The angle of this displacement will be denoted by a_2 . a_2 is so chosen with 30 respect to a_1 that the linear movement of the two laps with respect to the lens surfaces will be the same, so that the grinding or polishing action will be the same. This condition is fulfilled if the 35 formula

$$(1) \quad r_1a_1 = r_2a_2$$

is satisfied.¹ Before the motion was begun, the two laps 12 and 13 were substantially co-axial 45 with axes along the line C_1C_2 . After the completion of this displacement, the axis of the lower lap has remained undisplaced while the axis of the upper lap has moved to the position $C_2'P$. The point P represents the intersection of the 50 new axis of the upper lap with the original co-axis C_1C_2 .

It will now be shown that the point P where the new and the old axes intersect is substantially 55 constant, independent of the angle, for angles of such magnitude as would be used in actual practice. It can be shown from trigonometry that the distance from the fixed center C_1 of the lower lap to the point P is given exactly by the following formula

$$(2) \quad \overline{C_1P} = \overline{C_1C_2} \sin \left(\frac{r_1}{r_2} a_1 \right) / \sin \left[\left(1 - \frac{r_1}{r_2} \right) a_1 \right]$$

For sufficiently small angles, the sine of the angle 65 may be replaced by the angle with a high degree of accuracy. Making this approximation, I obtain, for small angles, the following formula

$$(3) \quad \overline{C_1P}_1 = \overline{C_1C_2} \frac{r_1}{r_2 - r_1}$$

where the subscript 1 on $(C_1P)_1$ indicates that the distance is given by the formula to the first approximation. To obtain a higher approximation valid for larger angles, I use two terms of the

series expansion for the sine of an angle, thus obtaining

$$(4) \quad (\overline{C_1P})_2 = \overline{C_1C_2} = \frac{r_1}{r_2 - r_1} \left[\frac{1 - \frac{1}{6} \left(\frac{r_1}{r_2} \right)^2 a_1^2}{1 - \frac{1}{6} \left(1 - \frac{r_1}{r_2} \right)^2 a_1^2} \right]$$

whence using Formula 3 I get

$$(4a) \quad (\overline{C_1P})_2 = (\overline{C_1P})_1 \left[\frac{1 - \frac{1}{6} \left(\frac{r_1}{r_2} \right)^2 a_1^2}{1 - \frac{1}{6} \left(1 - \frac{r_1}{r_2} \right)^2 a_1^2} \right]$$

where the subscript 2 on $(\overline{C_1P})_2$ indicates that the distance is given by the formula to the second approximation. This approximation is sufficiently precise for almost all practical purposes. It indicates that the point P is not strictly fixed but will change slightly during the course of the movement. In order to show how small this change actually is, in a practical case, let us assume that the angle a_1 is $\frac{1}{3}$ of a radian, that r_1 is $\frac{3}{4}$ ", r_2 is $2\frac{1}{2}$ " and that the thickness (t) of the lens is $\frac{1}{4}$ ". The distance $\overline{C_1C_2}$, which enters into all of these formulae, is in general given by

$$(5) \quad \overline{C_1C_2} = r_1 + r_2 - t$$

Applying this formula to the special case, I get $2\frac{3}{4}$ " for the distance $\overline{C_1C_2}$. The first approximation using Formula 3 gives $(\overline{C_1P})_1$ as 1.375 ". The second approximation using Formula 4 increases this distance by approximately $\frac{1}{6}$ of 1% to the value 1.383 ". For ordinary purposes, I may ignore this small variation in the position of the point P and regard P as a fixed or determined point in the motion of the system.

In discussing Fig. 1 and also Figs. 2a and 2b, I have merely considered the oscillatory motion of the upper lap. It will be understood that the lower lap is rotated about its own axis continuously in Figs. 2a and 2b, just as it is in practice in the case illustrated by Fig. 1.

The displacement obtained in passing from Fig. 2a to Fig. 2b may be regarded, then, as an angular displacement of the upper lap 13 about the point P. In an actual machine, presently to be described, the upper lap 13 is given a "constrained" motion about the point P, but this motion need not necessarily be an oscillation. It may be, and in practice preferably is, a "conical" motion; that is to say, a preferred form of motion is one in which the axis $\overline{PC_2}$ of the upper lap rotates about the line $\overline{C_1C_2}$, said axis making an angle a_1 minus a_2 with the line $\overline{C_1C_2}$. Moreover, as will be further discussed below, this angle is preferably varied slowly during the motion. In any case, the motion of the lap 13 is rigidly determined by the machine elements, except for small displacements from deflections and clearances and except for motion parallel to its own axis. By means of a weight or a spring, an axial load is applied to the upper lap 13 and this load is freely transmitted to the lens and to the lower lap because of the longitudinal freedom allowed the lap 13. Aside from small deflections and clearances of the machine elements and the rotation about its stationary axis $\overline{C_1C_2}$, the lower lap 12 is allowed no freedom. However, in order to provide for proper determination of the point P with respect to the spherical surface of the lower lap, the position of this lap is made vertically adjustable, as will hereinafter be described.

Returning to Fig. 2b and disregarding friction for the moment, the resultant forces between the

lens surfaces and the respective surfaces of the laps 12 and 13 will again be directed along the line $\overline{C_1C_2}$. Since this line does not pass through the center of area of contact between either lens surface and its corresponding lap, a non-uniform pressure will arise from this source corresponding to the non-uniform pressure distribution due to the second cause discussed under Fig. 1. However, the non-uniformity of pressure distribution due to the first cause discussed under Fig. 1 is very substantially reduced in my method, as will now be described.

Again, let it be supposed that the upper lap C_1 of Fig. 2b is being oscillated to the left, as indicated by the arrow $A'-1$ of that figure. The frictional forces on the upper surface of the lens will be directed as shown by the small arrows $A'-2$ (note that I am now discussing the frictional forces on the lens, whereas in Fig. 1 I was discussing the frictional forces on the lap 4). There will be a corresponding set of frictional forces on the lower surface of the lens 11 indicated by the arrows $A-5$. The resultants of the frictional forces $A'-2$ and $A-5$ will now be collinear, and all that remains are two couples mentioned parenthetically on page 2, line 39, as being generally negligible. Hence, there will be very little tendency arising from frictional forces to rock the lens 11; the non-uniformity of pressure arising from this source is therefore minimized.

This circumstance represents by itself a material gain in quality, because anything which tends to make the pressure distribution between the lens and the lap non-uniform makes it more difficult to obtain optically precise surfaces and increases the operating time. The conical motion of lap 13 discussed above offers another advantage in this respect. In conventional machines such as shown in Fig. 1, the oscillation gives rise to a periodic reversal of direction of motion and hence to a corresponding reversal in the frictional forces. As a result of this, there is a very small but none the less objectionable displacement of the lap 4 with respect to the lens 1 at the conclusion of each stroke. By using the conical motion for lap 13 as described above, this reversal of frictional forces is eliminated, and a correspondingly greater smoothness and stability of motion is obtained which enhances the performance of the machine.

The basic kinematics of the system shown in Figs. 2a and 2b is fundamentally the same as that of the conventional system shown in Fig. 1. In the case of Fig. 1, the position of the lap 4 at each point of the motion is uniquely determined except for possible slippage. Precisely the same remark applies to the lens in the system shown in Figs. 2a and 2b. That the latter system will actually function as I have here indicated will be shown by a geometrical or kinematical demonstration in the next paragraph, but I may state first that I have used systems such as that of Figs. 2a and 2b and of Figs. 3a and 3b and that these uses show that such systems do function as described.

The kinematical behavior of any link having a ball joint at each end is, except for friction, completely determined by the ball centers and is independent of the diameters of the balls. Except for frictional forces, therefore, whose effects have been fully discussed above and which may for present purposes be ignored, the lap 4 of Fig. 1 may be regarded as a ball jointed link, with the lens 1 and lap 4 constituting one ball joint and the ball 5a and its socket in the lap 4 constituting the other. The kinematic length of this ball jointed link is the distance between the centers

C_1 and C_2 . The difference in ball diameters is of no kinematic consequence whatever (ignoring friction, as I have agreed to do). Now imagine the ball $5a$ increased in diameter and imagine its substance changed from steel to glass. The lap 4 still acts as a ball jointed link. In this way, I have transformed Fig. 1 from a conventional lens machine to a new type of lens machine in which one surface of each of two lenses 1 and $5a$ (transformed) is being operated upon simultaneously. Now imagine a further change in which the material of the lap 4 is changed from cast iron to glass and the elements 1 and $5a$ that were glass in the previous transform are changed to cast iron. This changes the first transform of Fig. 1 into a second transform which operates simultaneously on both surfaces of a bi-concave lens, with the lens itself now acting as the ball jointed link. In a similar way, it can be shown that the lens 11 itself in Figs. 2a and 2b acts as a ball jointed link with centers at C_1 and C_2 (or C_2^1) of those figures. The fact that the centers C_1 and C_2 (or C_2^1) are, so to speak, inverted with respect to the positions of the centers in an ordinary ball jointed link, does not alter the kinematics. The following results of the discussion of this paragraph may be pointed out:

1. A lens machine is disclosed which operates simultaneously on one convex surface of each of two lenses.
2. A lens machine is disclosed which operates simultaneously on both surfaces of a bi-concave lens.
3. The proposition has been demonstrated that the systems disclosed herein will function as described, except in so far as frictional forces may interfere.

My system is most advantageously applied to lenses of relatively high curvature, but it can be employed on other types of lenses. Such lenses, it will be seen from the drawings Figs. 1-5b, have a thickness at the center that is substantially different from that at the edges.

I will now consider some of the other lens surface combinations shown in the drawings and show how the formulae (1-5 inclusive) given above may be applied to them. In Figs. 3a and 3b, I have shown a system which differs from the system of Figs. 2a and 2b in that both surfaces now have the same radius of curvature; that is to say, in the said formulae above, r_1 becomes equal to r_2 . In this case, it can readily be seen from formulae (3 or 4) that the point P moves off to infinity because $r_2 - r_1$ becomes zero in these formulae. This means that the required motion is an oscillation or rotation such that the angles α_1 and α_2 are always equal; that is to say, the axes of the two laps 12 , 13 of Figs. 3a and 3b remain parallel during the motion. Since this "parallel" motion is the limit of a conical motion (as P moves to infinity), it may still be properly called a conical motion. Fig. 3b has been constructed from Fig. 3a by the same steps as Fig. 2b was constructed from Fig. 2a, and requires no further description.

Figs. 4a and 4b treat the case where one of the surfaces is plane; that is, r_2 is put equal to infinity. The distance C_1C_2 likewise becomes infinite. It can be shown in this case that the Formulae 2 and 3 given above degenerate to the expression (for small angles) $C_1P=r_1$. Again, the point P in Fig. 4b acts as an approximately fixed center for the conical or oscillatory motion. In this case, the angle α_2 is zero; that is to say, in the

second part of the motion indicated in Fig. 4b, the upper lap 13 is moved parallel to itself.

As a final example, I have shown in Figs. 5a and 5b the case of a convex-concave lens. This case is derived from the formulae developed for Figs. 2a and 2b, mathematically speaking, by making r_2 negative. This makes the angle α_2 likewise negative. The appearances of the formulae are unchanged by this change of sign, but in applying the formulae the negative sign must be used before r_2 . With these modifications, Fig. 5b is constructed from Fig. 5a by the same steps as Fig. 2b was constructed from Fig. 2a. Again, the point P of Fig. 5 represents an approximately fixed point which is the center of the conical rotation or oscillation. These examples will suffice to show how the method can be applied to other combinations of lens surfaces, such as plano-concave, bi-concave, etc.

It is not to be construed from the preceding description that the point P as determined by the above formulae or constructions is the point at which the center of the oscillatory or conical motion must be accurately set in order to achieve satisfactory results by my method. Actual experience has shown that good results are obtained even if the center of oscillation or conical motion does not correspond closely with P . This point merely represents the position which the center of motion should have in order to have equal mechanical action on both surfaces of the lens; but, if for any reason one surface of the lens should grind out or polish out materially faster than the other, the setting can be changed by moving the motional center so as to increase the relative mechanical movement at the face where the grinding or polishing takes place more slowly.

Referring now to Figs. 6 to 9 inclusive, which illustrate a machine designed to carry out the operations indicated in the diagrams of Figs. 2a and 2b, 11 is the lens which is being ground or polished, 12 is the lower lap and 13 is the upper lap, all corresponding with Figs. 2a and 2b. The upper lap 13 is attached removably, for example, by means of the taper shown, to a rod $14b$ which has a sliding fit in the bore of the member 14 , which in turn has a sliding fit in the bore of a sleeve 16 ; the member 14 may be provided with a key 15 operating in a keyway $16a$ in order to prevent the member 14 from rotating in said sleeve 16 . However, I have obtained satisfactory results also in many cases by dispensing with the key 15 and keyway $16a$ and allowing the member 14 to "float"; the rod $14b$ is acted on by the spring $14c$; furthermore, the rod $14b$ has its longitudinal motion limited by the head of the screw $14d$ operating in the slot $14e$; the screw and slot arrangement $14d-14e$ also serves to prevent the rod $14b$ from rotating in the member 14 and functions desirably as a key in such cases where the key 15 and keyway $16a$ are employed. Sleeve 16 has an enlarged portion $16b$ at its lower end which is transversely bored to receive the small ends of the pins 17 . The large ends of these pins are held suitably as by set screws $17a$ in the arms $18a$ of the fork member 18 whose body portion $18b$ is bored to receive the bushings 19 which have a bearing fit on the headed stud shaft or pin 20 . The fork 18 is longitudinally positioned by the head of the pin 20 and the collar 21 . The outer end of the pin 20 is suitably clamped in the bracket 22 as by means of a split in said bracket and a clamping bolt $22a$ which

serves to tighten the bracket around said shaft or pin 20.

By the construction shown, the sleeve 16 is universally pivoted. The center of this system of pivots is provided by the intersection of the axis of shaft or pin 20 with the axis of pins 17. This point of intersection is indicated by P in Fig. 6 and corresponds to the center of conical motion or oscillation indicated by the point P in Fig. 2b. Any other suitable universal coupling of sleeve 16 to provide such center P may be used.

The upper end of the member or slider 14 terminates in a ball socket in which is seated the ball 23a of the ballpin 23. The ball is retained in its socket suitably as by means of the cap 14a screwed onto the end of the slider 14. The ballpin 23 is rigidly held (as by means of a taper pin 23b shown in Fig. 8) in the swinging arm 24 which has a bearing fit on the shaft 25 and is held thereon by collar 25b. Washers 25c are employed as indicated to minimize friction and wear as the arm 24 swings back and forth on shaft 25.

The shaft 25 has an extension 25a which protrudes through a lower disc 30 and threadedly engages in an upper disc 29. A suitable spacer 26 is provided on said extension 25a between said discs 29 and 30. Other suitable bolts 27 and 28, each carrying similar spacers 26 serve to maintain the two discs in rigid fixed spaced apart relationship. These two discs 29 and 30, together with the gears to be described, constitute what I shall call, for convenience, the "gear box."

A central pin 31 is rigidly attached (e. g., by means of a force fit and a pin 31a) to the lower disc or plate 30. This pin has a bearing fit in a pinion 32, whose hub 32a is rigidly fastened as by means of a force fit to the arm 43, which in turn engages the suitably supported rod 44, whose function is to prevent the arm 43 (and hence the pinion 32) from rotating. Meshing with the pinion 32 is the gear 33 which drives the member 34, which latter has a force fit in the gear 33. The member 34 is rotatably supported by the discs 29 and 30 and acts as a shaft for the gear 33, and has an enlarged portion milled with a T slot 34a. The square head 35a of a bolt 35 fits slidably in this T slot. A flanged bushing 37 has a clearance fit on the pin 35. The outside diameter of this bushing 37 has a bearing fit in a member 38. The parts 37 and 38 are so fitted that, when the nut 36 is tightened on the bolt 35, they will be solidly clamped together with member 34 and yet permit free rotation of member 38 on the bushing 37. In this way, the pin 35 is locked in any adjusted position in the T slot 34a without binding member 38. Other suitable means for effecting this result may be employed. A slotted bar 41 is clamped at its slotted end 41a to an extension 38a of the member 38 (Fig. 9a) by means of bolt 39. When so clamped, bar 41 and member 38 are rigid relative to each other. At its other end, bar 41 is clamped similarly by bolt 40 to an extension 42a of the member 42 which has a bearing fit on the shank of the ballpin 23 and is otherwise similar to the member 38. The members 38 and 42 and bar 41 together constitute an adjustable connecting rod which connects the pin 35 to the ballpin 23. By means of this arrangement, as the discs 29 and 30 rotate as will be presently described, gear 33 has planetary rotation about the pinion 32. The member 34 rigid with gear 33 also rotates and the eccentric pin 35 is then rotated around the common axis of the gear 33 and member 34, and by

means of the "connecting rod" assembly this rotation is converted into an oscillating movement of the ballpin 23 with the arm 24 about the shaft 25.

5 The lower lap 12 is removably held, for example by means of a taper connection, on a cap member 51 which is threaded onto bearing 52 fitted with bushings 53, which have a bearing fit on the stationary hollow spindle 54. Spindle 54 is solidly attached, for example by means of a drive fit, to the flange 55. Clamped between the cap 51 and the bearing 52 is a cup 56 which is recessed to receive the head 57a of the rod 57 together with washers 56a above and below said head 57a, as indicated in the drawings. It will be understood that the head 57a is free to turn in the cup 56; that is, after the cup 56 is clamped between the cap 51 and the bearing 52, the head 57a will have both radial and longitudinal clearance. The rod 57 has a threaded portion 57b which engages the corresponding thread in the lower end of the stationary hollow spindle 54. The lower end 57c of part 57 is adapted to take handle 58. By turning this handle, the rod 57 is raised or lowered, thereby raising or lowering the cap-and-bearing assembly and with it the lower lap 12. This provides a fine adjustment for bringing the center of curvature of the lower lap 12 into proper relationship with the center P of the conical motion. Once the height of the lower lap has been adjusted, it is locked in position by the arm 59 which carries a threaded boss serving as a jam nut. The bearing member 52 is provided with a portion 52a which acts as a pulley.

The foregoing parts have been so designed that they may be readily attached to a commercial form of bench type drill press. Only such portions of the drill press are shown in the drawings as are necessary to indicate how these parts are to be mounted. The drill press has a base 61 to which the flange 55 is attached; for example by means of bolts not shown. In attaching flange 55 to the base 61, it is desirable to bring the stationary spindle 54 into good alignment with the spindle of the drill press (not shown). The drill press has a post 62 which carries its upper mechanism (not shown) including its spindle. These drill presses are normally provided with a "tilting" table which can be adjusted vertically on the post by means of the part 63, and rotationally by means of the stub 63a. The tilting table is removed and the stub 63a is used for mounting the bracket 22 on the drill press, said bracket being clamped on the stub 63a by means of a split and clamping bolt 22b. As usual, the spindle of the drill press carries at its lower end the drill chuck 64. The central pin 31 of the "gear box" is fastened in the drill chuck in the same manner as a drill is fastened. The drill press is also normally provided with a collar (not shown) which moves up and down with the spindle but does not rotate with it. The rod 44 is attached to this collar and prevents the arm 43, hence the pinion 32, from rotating by engaging said arm as previously described.

It will be understood that the lower bearing assembly is rotated by means of a belt and the pulley portion 52a. Also, that the drill chuck 64 is rotated in the conventional way. These two rotations may be in the same or opposite directions. The means for achieving these rotations are conventional and need not be further described.

In order to apply the desired pressure, it is merely necessary to bring down the drill chuck

by the same operation as if one were drilling a hole. The amount of pressure is determined by the extent to which the spring 14c is compressed in bringing down the drill chuck. When the chuck has been lowered to the extent necessary to create the desired pressure, it can be locked in that position by a mechanism usually provided on such drill presses for the purpose.

As the drill chuck 64 rotates, it rotates the discs 29 and 30 and, through the "gear box" connections described, carries the ballpin 23 around an orbit which would be circular if said ball pin were held stationary in an eccentric position with respect to the "gear box" (e. g., by adjusting the pin 35 in slot 34a to zero eccentricity relative to the axis of member 34). This circular motion would impart a conical motion to the slider 14, and from the construction of the mechanism, it is obvious that the center of this conical motion would be at the point P, as heretofore explained. However, the motion of the ballpin is not strictly circular but is in the form of a "spiral" which goes from maximum diameter to minimum diameter, then back to maximum again, cyclically. This spiral motion is produced as follows. As the drill chuck 64 rotates, it rotates the gear box discs 29 and 30 around with it by means of the pin 31. Now, since the pinion 32 does not rotate, the gear 33 acts like a planetary gear and is caused to rotate about its axis. If the gear ratio is n , then n revolutions of the gear box will be required for one spiral-cycle. (Note that I am here concerned with the rotation of the gear 33 with respect to the "gear box," and this is the same as that given by the ordinary "gear ratio," no matter whether pinion 32 rotates and the gear box is held stationary, or vice versa.) In the machine shown in the drawings, the value of n is nearly 3 (n should preferably not be an integer). As the gear 33 rotates on its axis, it rotates member 34 with it and carries the eccentric pin 35 around in a circular path, the radius of which depends upon the position of the pin 35 in the T slot 34a. This circular motion of the eccentric pin 35 is communicated as an oscillatory motion to the ballpin 23, as heretofore described, and the combined motions of the ballpin give rise to a compound conical motion of the slider 14 such that the cone angle varies periodically from maximum to minimum and back. The center of this compound conical motion is again at P. The mean angle of the conical motion is adjusted by adjusting the length of the "connecting rod," heretofore described. The amplitude of the cone angle variation is adjusted by adjusting the position of the pin 35 in the T slot 34a.

The arrangement of slider 14 and universally pivoted sleeve 16 is not suitable for the "parallel" case shown in Figs. 3a and 3b, for reasons heretofore set forth. To provide for this case, the arrangement shown partially in section in Fig. 10 and in plan in Fig. 11 is used. The slider member 14 is unchanged including means for attaching the upper lap 13 and the ballpin 23, but instead of the universally pivoted sleeve 16, a pair of pivoted arms 71-72 is employed. The slider 14 slides in the boss 71a of the arm 71, which may be provided with a keyway to receive the key 15 as before. At its other end, the arm 71 is pivoted to the arm 72 by means of the lugs 71b and pin 73. At its free end, the arm 72 is pivotally attached to the bracket 22 by pin 74. By this construction, the slider 14 is constrained to remain parallel to itself throughout its motion.

The motion imparted to the slider 14 by the ballpin 23 driven as described is again a mean circle on which is superimposed a slow radial oscillation causing the motion to proceed as before in the form of ever-waning and waxing spirals between maximum and minimum limits prescribed by the eccentricity of the pin 35.

It may be pointed out that the "parallel" arrangement of Figs. 10 and 11 may be employed, not only where the two lens surfaces are equal in radii, but also where they are nearly equal. It will be noted that in the formulae given earlier in this specification, the difference r_2 minus r_1 of the radii of the lens surfaces appears in the denominator for the expression giving the location of the point P with reference to the center of the lower lap surface. If r_2 and r_1 are nearly equal, the corresponding distance of the point P will be large on this account. When this distance is fairly large, no serious error arises in ordinary cases from regarding the point P as lying at infinity and using the parallel linkage instead of the "conical" linkage of Figs. 6 and 7. Moreover, as was pointed out above, it is not necessary for the satisfactory functioning of my machine that the actual center of oscillation or conical motion coincide closely with the theoretically determined point P.

In all lens grinding and polishing operations, it is necessary to use grinding or polishing media which, in conventional methods, are fed periodically to the surfaces being worked; e. g., by means of a brush. The method of finishing lens surfaces here proposed permits of a more efficient and less laborious way of handling the grinding and polishing media. For this purpose, I propose to employ a cup member 81 which may be carried on the lower lap 12 as indicated in Fig. 6, with the joint between 81 and 12 rendered watertight, e. g., by means of a wax layer 82, or in any other suitable way. The grinding or polishing compound is placed in the cup at a sufficient height to cover the lens. The process of operating the machine will keep the mixture stirred; but, if this is not sufficient, additional stirring means (not shown) may be employed. The grinding or polishing medium must, of course, be replenished and in particular evaporation must be allowed for, e. g., by adding small quantities of water at intervals. However, the attention which must be given to the machine by the operator is very much reduced by this method of feeding. Moreover, this method is less likely to give rise to unequal friction at the two lens surfaces.

The motion given to the upper lap 13 by the "gear box" and the slider 14 has been described as a conical motion centered at P, with the angle of the cone varying periodically from a minimum to a maximum and back. By inverting the gear ratio; that is, by interchanging the positions of pinion 32 and gear 33, the motion becomes one which can be described as an oscillation with the plane of oscillation being continuously rotated. The latter type of motion has some advantages.

While I have described mechanisms for obtaining motions differing from the simple oscillatory motion conventionally used in lens grinding (combined with the rotary motion of the other member), it is not to be construed that my machine is not capable of use with such simple motion of the upper lap. This is far from being the fact. I have not shown my machine adapted for such simple oscillatory motion for the rea-

son that such motions and the methods for producing them are too well-known to require description. Modifications of my machine necessary for obtaining such simple oscillatory motions will be readily understood by any one skilled in the lens grinding art. Many other modifications are feasible, for example, the modification in which an oscillatory motion is employed (as distinct from a conical motion) but in which the amplitude of oscillation is periodically varied as by means of a gear box structure similar to that shown in Figs. 8, 9 and 9a. Furthermore, modifications in the adjustment or the design of the machine in order to accommodate it to other combinations of lens surfaces; for example, those shown in Figs. 4a to 5b inclusive, will also be readily understood and require no further description.

There are a great many other modifications which may be made in the structure and operation of the machine. To mention just a few, I have found that the machine will operate with the gear box and upper driving mechanism completely eliminated and with the center of the conical motion displaced off the axis of the lower spindle. Furthermore, I have found that, even when the center of the conical motion is approximately on the axis of the lower spindle, with the gear box removed as before, but with a weight placed on the member 14, oscillations of the upper mechanism may be self-induced. Or, using the gear box, the lower lap may be held stationary or left free. Mention of these modifications is not to be construed as a limitation.

While I have described my method as operating on both surfaces of a single lens, and as particularly adapted for such purposes, it should not be construed that the method can not be applied to operations on a group of lenses corresponding to the group method employed in conventional practice. By mounting two groups of lenses on a lenticular shaped block, one group being mounted on each face of said block, my method may be employed to operate simultaneously on the exposed surfaces of the lenses of both of said groups. In this application, the advantage of the elimination of the pitch mounting of lenses on a block is lost but certain other advantages are gained. The word "lens" as used in the claims shall be interpreted to mean either a single lens or a double group of lenses.

Whether operating on two surfaces of a single lens or on the surfaces of two groups of lenses, a characteristic of my machine is that the two laps have a relative oscillatory or conical movement centered at a point which is not at the center of any of the lens surfaces and whose location is determined approximately by Formula 3. As pointed out above, the location may vary substantially from this position, and the use of the word "approximately" is to be understood in that sense.

It is a familiar fact to those engaged in the lens polishing industry that, during the polishing operation (with laps faced with pitch and with rouge mud as a medium), a considerable amount of suction and friction develops between the surface of the lens and the surface of the pitch lap. When this suction becomes excessive, it is common practice to groove the surface of the pitch lap and the grooving is so made as to create larger pressures where they are desired in the course of polishing. A feature in conventional lens polishing methods which has not apparently been hitherto recognized, however, is the fact

that the tilting action described in connection with Fig. 1 is sufficient to lower the frictional drag very materially. In my machine, however, where, as previously pointed out, such tilting actions are minimized, the suction and frictional drags become so great that the pitch of the pitch lap is subjected to stresses which may cause it to break down. I have overcome this difficulty by substituting for the pitch conventionally used a layer of cellulose acetate made by melting in situ on the lap chips of highly plasticized cellulose acetate such as is used for molding purposes. The face of the cellulose acetate which bears against the lens is shaped by the same method as is employed in shaping pitch laps. I prefer to carry the melting of these chips just so far that the uppermost chips are not fully melted, so that, after the forming of the face of the lap, the surface of the cellulose acetate is covered with cracks. I have also found that such laps may be grooved in much the same way as pitch laps are grooved. Such laps have a considerable amount of "cold flow" which is characteristic of pitch, but this cold flow of the acetate lap may be increased by application to the surface of a small amount of "swelling agent" or "plasticizer" with some solvent action.

I have used the term "lower lap and upper lap" to indicate respectively the lap which has rotary motion about its axis and the lap which is oscillated or moved conically about a fixed center. In the claims, the words "lower" and "upper" are to be construed in this sense and not necessarily as meaning that the one lap must be below the other.

The conical motion about the point P which the machine shown in Figure 6 provides can be looked upon as a compounding of two simple oscillations in two planes at 90° and with phases 40 90° apart. For convenience, in the claims I shall use the word "oscillation" to mean either a simple oscillation or any compounding of such oscillations so as to produce conical motions or any other type obtainable by such compounding.

41 I have described the general nature of this invention and have also described some particular embodiments of the invention in the form of practical machines for finishing of lens surfaces (by finishing is meant any of the operations: smooth grinding, fine grinding, polishing).

While specific embodiments of machines for carrying out my invention have been described, it is to be understood that variations in structural detail are contemplated within the scope 55 of the claims. There is no intention of limitation to the exact details shown and described.

I claim:

1. A method of finishing opposite surfaces of a lens simultaneously and substantially to the same extent, comprising providing laps each having a finishing surface shaped complementary to that of the lens surface with which it is to engage, positioning said lens between said finishing surfaces so that its respective surfaces are in pressure engagement with the respective complementary-shaped finishing surfaces of said laps, and, while maintaining said pressure, rotating one of said finishing surfaces about a fixed axis, and simultaneously oscillating the other of said finishing surfaces about a pivot point determined approximately by Formula 3 of the specification whereby the relative motion between said finishing surfaces on said lens surfaces will effect said finishing of both said lens surfaces.
2. A method of finishing opposite surfaces of

a lens simultaneously and substantially to the same extent, comprising providing laps each having a finishing surface shaped complementary to that of the lens surface with which it is to engage, positioning said lens between said finishing surfaces so that its respective surfaces are in pressure engagement with the respective complementary-shaped finishing surfaces of said laps, and, while maintaining said pressure, supplying finishing media to each of said finishing surfaces, rotating one of said finishing surfaces about a fixed axis, and simultaneously oscillating the other of said finishing surfaces about a pivot point determined approximately by Formula 3 of the specification whereby the relative motion between said finishing surfaces on said lens surfaces will effect said finishing of both said lens surfaces.

3. A method of finishing opposite surfaces of a lens simultaneously and substantially to the same extent, comprising providing members having oppositely disposed finishing surfaces each complementary to that of the lens surface with which it is to engage, positioning said lens between said finishing surfaces so that the respective lens surfaces are in pressure engagement with the respective complementary-shaped finishing surfaces, and while maintaining said pressure engagement, rotating one of said finishing surfaces about a fixed axis and simultaneously moving the other finishing surface so that an axis passing through the latter moves about a pivot point determined approximately by Formula 3 of the specification to describe a cone whose cone angle varies periodically whereby the relative motion between said finishing surfaces on said lens surfaces will effect said finishing of both said lens surfaces.

4. A method of finishing opposite surfaces of a lens having substantially different thickness through its center than at its periphery simultaneously and substantially to the same extent, comprising providing members having oppositely disposed finishing surfaces each complementary to that of the lens surface with which it is to engage, positioning said lens between said finishing surfaces so that the respective lens surfaces are in pressure engagement with the respective complementary-shaped finishing surfaces of said members, and, while maintaining said pressure engagement, rotating one of said finishing surfaces about a fixed axis, and simultaneously moving the other of said finishing surfaces along an orbital path that varies periodically in amplitude whereby the relative motion between said finishing surfaces on said lens surfaces will effect rotary and oscillating motion of the lens and said finishing of both said lens surfaces while the position of the lens between said finishing surfaces will at all times be uniquely determined by virtue of the kinematic reactions between coacting surfaces of the lens and the laps.

5. In apparatus of the class described, a first lap having a surface whose shape is complementary to that desired on one face of a lens of relatively high curvature, a second lap having a surface complementary to that desired on the opposite face of said lens, means for rotating the first of said laps about a central axis, means for imparting an oscillatory motion to the second of said laps about a center determined by the shape of the said faces of said lens and approximately by Formula 3 of the specification, and means for pressing said surfaces against said faces of said lens to finish said opposite faces simultaneously

and substantially to the same extent, the position of said lens between the surfaces of said laps being at all times uniquely determined by the co-action of the lens and said surfaces.

6. In apparatus for the finishing of opposite surfaces of a lens simultaneously and substantially to the same extent, oppositely disposed laps having finishing surfaces between which the said lens is positioned, means for supporting one of said laps, means for adjusting the position of said one of said laps with respect to the other of said laps, means for rotating said one of said laps about a central axis, universally pivoted means for supporting the other of said laps, means for moving said other of said laps to effect motion thereof about a center provided by said universally pivoted means and determined approximately by Formula 3 of the specification, whereby, when the said lens has its opposite surfaces engaged by said respective finishing surfaces, said rotation of the said first of said laps and the said motion of the other of said laps about its said determined center will cause said finishing surfaces to effect said finishing of said lens surfaces.

7. Apparatus for finishing the oppositely directed surfaces of a lens simultaneously and substantially to the same extent comprising a lap having a finishing surface complementary in shape to that of one surface of said lens, means for rotating said lap about a fixed axis, means for adjusting said lap along said axis, a second lap having an oppositely directed finishing surface complementary in shape to the other surface of said lens, said finishing surfaces being adapted to receive between them the said lens, axially slidable means for carrying said second lap, universally pivoted means for supporting said axially slidable means, and means for imparting oscillatory rotary motion to said axially slidable means about a center provided by said universally pivoted means and determined approximately by Formula 3 of the specification, whereby said slide means and said second lap have compound conical motion imparted thereto whose cone angle about said determined center varies periodically.

8. Apparatus for finishing opposite surfaces of a lens simultaneously and to substantially the same extent comprising a lap having a finishing surface, means for rotating said lap about a fixed axis, a second lap having an oppositely directed finishing surface, said finishing surfaces being adapted to receive between them the said lens, axially slidable means for carrying said second lap, universally pivoted means for supporting said axially slidable means, means for imparting oscillatory rotary motion to said axially slidable means about a center provided by said universally pivoted means and determined approximately by Formula 3 of the specification, whereby said slide means and said second lap supported thereon have compound conical motion imparted thereto whose cone angle varies periodically about said determined center.

9. Apparatus as per claim 5 in which a receptacle is provided in association with said laps adapted to contain finishing media, said receptacle being so positioned that its contents are agitated by the movement of said laps and distributed directly to said lap surfaces.

10. Apparatus as per claim 5 in which means are provided for supplying finishing media to said lap surfaces during finishing operations by said laps.

11. Apparatus for finishing the opposite sur-

faces of a lens having substantially different thickness through its center than at its periphery simultaneously and substantially to the same extent, comprising a lap having a finishing surface, means for rotating said lap about a fixed axis, a second lap having an oppositely directed finishing surface, said finishing surfaces being adapted to receive the said lens between them, axially slid-
able means for carrying said second lap, pivoted means for supporting said axially slidable means, means for imparting rotary motion to said slidable means and motion to the said second lap sup-
ported thereon such that the orbital amplitude of said second lap varies periodically, and means for applying pressure between engaging lens and finishing surfaces whereby rotary and oscillatory motion of said lens and said finishing of said lens surfaces are effected, and the position of said lens between the surfaces of said laps is at all times uniquely determined by virtue of the kinematic reactions between the coacting surfaces of the lens and respective laps, said means for imparting motion to said second lap comprising a stationary gear, a second gear movable around said stationary gear with planetary motion, a rotatable member carrying said second gear, means for rotating said rotatable member, an oscillatory mem-
ber supported from said rotatable member, means

coupling said oscillatory member to said axially slidable means, and adjustable means coupling said oscillatory member to said second gear.

12. In apparatus for the finishing of opposite surfaces of a lens simultaneously and substan-
tially to the same extent, a lower lap and an upper
lap having finishing surfaces between which the
said lens is positioned, means for supporting said
lower lap and for adjusting its position relative
to the upper lap, means for rotating said lower
lap about its axis, universally pivoted means for
supporting the upper lap and means for moving
it about the center provided by said universally
pivoted means and determined approximately by
Formula 3 of the specification, whereby when said
lens has its opposite surfaces engaged by said
respective finishing surfaces, the rotation of the
lower lap and the motion of the upper lap about
the said center will cause the finishing surfaces
to effect the finishing of said lens surfaces.

13. In a lens finishing machine, a pair of op-
positely disposed laps having finishing surfaces
complemental to the lens surfaces to be finished,
means for rotating one of said laps and means
for oscillating the other of said laps about a point
determined approximately by Formula 3 of the
specification.

BENJAMIN LIEBOWITZ.
